UNITED STATES PATENT OFFICE.

GEORGE H. PROUT, OF LOS ANGELES, CALIFORNIA.

SUCKER-ROD HANGER.

Application filed February 13, 1924. Serial No. 692,484.

To all whom it may concern:

Be it known that I, GEORGE H. PROUT, a citizen of the United States, residing at Los Angeles, in the county of Los Angeles, 5 State of California, have invented a new and useful Sucker-Rod Hanger, of which the following is a specification.

This invention relates to pumping equipment of the character used in pumping oil 10 and water from deep wells.

The polish rod from which extends the string of sucker rods leading to the pump plunger, projects vertically upward from the stuffing box of the tubing head. This 15 polish rod should be reciprocated in a vertical direction without flexure. The present common form of reciprocating means used for oil wells consists of a horizontal walking beam which is pivoted at the center 20 thereof and has the rearward end linked by a connecting rod to a crank associated with the band wheel. At the forward end of the walking beam, a hanger is employed which makes pivotal connection with the 25 polish rod. Owing to the fact that the walking beam is pivoted, the reciprocation of the forward end thereof follows an arcuated path generated about the point of pivot of the walking beam. This curved 30 movement of the upper end of the hanger causes the sucker rod to be bent to the side at each reciprocation. This causes considerable strain on the sucker rod and produces a preponderance of wear on one side there- 35 of which results in leakage of the stuffing box.

It is a principal object of my invention to provide a simple means for reciprocating the sucker rod in substantially vertical 40 alignment so that excessive flexure will not be placed therein as now done by the use of the ordinary type of sucker rod hanger.

It is a further object of the invention to make the hanger in such form that it may 45 be quickly removed from the walking beam without necessity of removing bolts or nuts.

Referring to the drawings which are for 50 illustrative purposes only,

Fig. 1 is an elevational view showing an 55 embodiment of my invention.

Fig. 2 is a view taken from the line 2—2 of Fig. 1.

Fig. 3 is a diagrammatic view representing 55 the action produced in the sucker rod hanger.

As shown in Figs. 1 and 2, my invention employs a mounting plate 11 which has extending trunnions 12 and which is placed on the forward end 13 of a walking beam 14. The plate portion 15 of the member 11 has 60 downwardly extending dogs 17 which project into the wood of the walking beam and prevent lateral displacement of the member 11. From the trunnion 12, a hanging means preferably in the form of straps 20, extends 65 downwardly and is received upon a shaft 21. From the shaft 21, further suspending means which may also be metal straps 22 are employed for supporting a sucker rod yoke 24 having a central opening through 70 which the sucker rod upwardly projects as shown in Fig. 2, and having flat upper and lower faces against which the sucker rod clamps 25 may bear. On the under sloping face 27 of the walking beam 14, a fixture 75 28 is placed. This fixture employs a plate 29 arranged to rest against the face 27 and diagonally extending arms 30 which are parallel in disposal and have slots 31 cut inwardly from the outer ends thereof. Between the shaft 21 which is situated at the lower end of the suspending means formed of the members 20 and the fixture 28, there extends a strut member 33 comprised of a 80 pair of substantially rigid diagonal bent 85 bars 34 which extend in the same inclined head between the arms 30 of the fixture 28 and are equipped with a projecting pin 37 which engages the slots 31. The action produced by this construction will be made 90 evident from Fig. 3. In Fig. 3, the walking beam 14 is diagrammatically indicated. This walking beam is pivoted at 40 on the top of a post 41. When the walking beam 95 is reciprocated by the link 42, any point in the walking beam follows an arc concentric with the hinge 40. Therefore, it will be recognized that the trunnions 12 will follow a path 13 when the forward end 100 of the walking beam travels upwardly. This in ordinary circumstances causes the polish rod to be bent considerably to one side. It will be further recognized that at the start of the upward stroke of the walking beam, the deflection is relatively small, 105 but as the end of the stroke is reached, the flexure or disalignment is considerably increased. Therefore, if the point indicated by the trunnions 12 were to be reciprocated through a very short distance substantially 110

upon the horizontal axis A—A, the flexure in the polished rod would be substantially imperceptible.

It is the idea of my invention to provide a means which will come into play as the trunnions 12 move beyond the limits of the short travel just discussed and will prevent the lateral pull exerted by the trunnions 12 as they travel over the path 13 from deflecting the sucker rod. The strut member 33 accomplishes this result.

It will be noticed that the point of engagement, otherwise the shaft 21, is situated below the axis A—A, therefore, at the initial part of the upward stroke, the shaft 21 would travel forwardly along the arc 50, were it not for the play allowed between the pin 37, Fig. 1 and the bottom of the slots 31. Instead of moving outwardly along the arc 50, the shaft 21 may move upwardly until the axis A—A is nearly reached, whereupon the pin 37 will seat in the bottom of the slots 31 and the strut means 33 will then receive the thrust produced by the disalignment of the trunnions 12 in traversing the arc 13. The relative positions of the suspension means, otherwise the bars 20, and the strut means 33 are shown in dotted lines 55 in Fig. 1.

30 The hanger plate 15 may be lifted from the walking beam by engaging the eye 57, Fig. 2 and the pin 37 will slip readily from the open slots 31, thus permitting the hanger to be hoisted out of the way by use of tackle, 35 without necessity of removing bolts or nuts. This equipment is very simple in construction and confines the flexure of the sucker rod to very small limits, thereby reducing the uneven wear and the harmful effects of 40 constant flexure to a minimum.

I claim as my invention:

1. In a sucker rod hanger arranged to maintain substantial alignment of the polish rod, the combination of: a shaft hanging means extending vertically downwardly from the end of a walking beam pivotally connected at the lower end to said shaft; and a rigid diagonal strut pivotally connected to said shaft and extending therefrom to an interior point on said walking beam; and means permitting a limited movement of said strut.

2. In a sucker rod hanger arranged to maintain substantial alignment of the polish rod, the combination of: hanging means extending vertically downwardly from the end of a walking beam; and strut means extending between the lower end of said hanging means and an interior point on said walking beam, said strut means being

limited in its movement by engagement with the walking beam and arranged to provide a relatively small relative movement between the lower end of said hanging means and said interior point on said walking beam.

3. In a sucker rod hanger arranged to maintain substantial alignment of the polish rod, the combination of: hanging means extending vertically downwardly from the end of a walking beam; a fixture having a slot, mounted at an interior position on said walking beam; and a strut member having one end secured to the lower end of said hanging means and the other end received in 75 the slot of said fixture.

4. In a sucker rod hanger arranged to maintain substantial alignment of the polish rod, the combination of: hanging means extending vertically downwardly from the end of a walking beam; a fixture mounted on said walking beam having a slot, said slot being open at the outer end; and a strut member extending between the lower end of said hanging means and said fixture, said strut member being pivotally secured to said hanging means and being removably secured to said fixture by means of a pin, said pin resting in said slots of said fixture.

5. In a sucker rod hanger arranged to maintain substantial alignment of the polish rod, the combination of, a walking beam, trunnions mounted on said walking beam, a shaft, a strap on each side of the walking beam pivotally mounted at their upper ends 95 on said trunnions and at their lower ends on said shaft, a sucker rod yoke, a second pair of straps pivotally connected at their upper ends on said shaft, and at their lower ends on said trunnion, and strut means 100 pivotally connected to said shaft at one end and movably connected to said walking beam at the other end.

6. In a sucker rod hanger arranged to maintain substantial alignment of the polish rod, the combination of, a walking beam, trunnions mounted on said walking beam, a shaft, a strap on each side of the walking beam pivotally mounted at their upper ends on said trunnions and at their lower ends on said shaft, means connecting said shaft with the sucker rod, and strut means pivotally connected to said shaft at one end and movably connected to said walking beam at the other end.

In testimony whereof, I have hereunto set my hand at Los Angeles, California, this 8th day of February, 1924.

GEORGE H. PROUT.
